UNITED STATES PATENT OFFICE

162,756

DECK OF PLAYING CARDS

William L. Shriner, Oklahoma City, Okla.

Application September 6, 1949, Serial No. 4,858

Term of patent 14 years

(Cl. D34—13)

To all whom it may concern:

Be it known that I, William L. Shriner, a citizen of the United States, residing at Oklahoma City, in the county of Oklahoma, and State of Oklahoma, have invented a new, original, and ornamental Design for a Deck of Playing Cards, of which the following is a specification, reference being had to the accompanying drawings, forming part thereof.

Fig. 1 is a front view of the twenty cards constituting the "star" suit in the deck of playing cards, showing my new design;

Fig. 2 is a front view of the twenty cards constituting the "spot" suit therein; and

Fig. 3 is a front view of the twenty cards constituting the "spear" suit therein.

The cards are of no appreciable thickness, and the backs thereof may be plain or conventional.

I claim:

The ornamental design for a deck of playing cards, as shown and described.

WILLIAM L. SHRINER.
